RECONDITIONING CATALYTIC CYCLE STOCKS

Alfred A. Wells, Roselle Park, N. J., assignor to
 Standard Oil Development Company, a corporation of Delaware

Application June 24, 1940, Serial No. 342,031

1 Claim. (Cl. 196—52)

The present invention relates to the art of treating hydrocarbons. More particularly, the present invention relates to improvements in the catalytic treatment of relatively heavy hydrocarbons such as a gas oil to form fractions boiling within the gasoline range, in which process the cycle stock, that is to say, the unconverted hydrocarbons recovered from the catalyst zone are subjected to a conditioning operation in order to improve their cracking characteristics or properties when recycled to the cracking zone.

It is generally known that in the cracking of hydrocarbons thermally, the charging stock should be largely paraffinic to produce the best results. It is also known that the more a charging stock is cracked thermally, the poorer it becomes as a feed stock for further cracking. Consequently, in thermal operations there comes a time when the feed stock, due to repeated cracking, must be rejected from the system because it becomes too refractory and has too great a tendency to form excessive coke to be suitable for further treatment.

On the other hand, the feed stock for a catalytic cracking operation is preferably of a naphthenic character and should also be free, or substantially so, of aromatic compounds containing more than one benzene ring in a single condensed nucleus. If a feed stock used in a catalytic cracking operation contains compounds such as naphthalene, anthracene, phenanthrene, benzanthrene and the like, or their alkylated derivatives, these condensed ring compounds form, during the cracking operation, excessive quantities of coke. Furthermore, if a feed stock in a catalytic cracking operation contains substantial quantities of olefins, and especially the diolefins or poly-olefins, these latter compounds during the catalytic cracking operation tend to polymerize to form high molecular weight hydrocarbons which, during the catalytic conversion, are converted to tarry or gummy deposits or coke which deposit on the catalyst and necessitate frequent shutdowns for the purpose of removing the same and regenerating the catalyst.

I have discovered means for conditioning the cycle stock or recycled oil recovered from a catalytic operation wherein the same is improved as to its cracking properties and therefore may be recycled to the catalyst zone for further conversion without causing excessive formation of tarry deposits or coke on the catalyst.

It is an object of my invention to condition an oil such as a cycle oil recovered from a catalytic process, which oil is not satisfactory from the

standpoint of cracking characteristics, by subjecting the said oil to a catalytic treatment wherein the tar-forming constituents are converted to high molecular weight compounds which may be removed from the said oil so that the said oil may be returned to the cracking zone for further treatment with the assurance that such treatment will not result in the formation of excessive quantities of coke.

10 A proper understanding of my invention will be had by reference to the accompanying drawing in which the figure represents in diagrammatic form, an apparatus layout in which my process may be carried into practical effect.

15 Referring in detail to the drawing, a feed stock such as a virgin gas oil having an A. P. I. gravity of 25° is fed to the system through line 1 and thence discharged into a coil 2 disposed in a furnace setting 3 where the hydrocarbon oil is heated to cracking temperatures, say a temperature of about 825° F. The hydrocarbon vapors are withdrawn from the furnace through line 4 and discharged into a catalytic cracking chamber 6, where the vapors contact a cracking catalyst

20 such as an acid treated clay, and under the conditions specified the gas oil vapors are converted to gasoline in yields amounting to 40%—50% of the original feed stock. The total vapors are withdrawn from the reaction vessel 6 through a vapor line 10 and then passed into a fractionating column 12 where the vapors are fractionated, the gasoline fraction being withdrawn overhead through line 14, thence discharged into a condenser 16 where the gasoline vapors are liquefied, thence discharged through line 18 into a receiving drum 19 from which the gasoline may be recovered through line 20. Meanwhile, heavy oil or a high boiling fraction is withdrawn through line 21, while a lighter or lower boiling

30 fraction is withdrawn through line 22, the latter being thence discharged into coil 23 disposed in a furnace 24 where the unconverted gas oil is heated to a temperature sufficient to vaporize the same, say a temperature of 600°—800° F. The oil vapors are withdrawn from the furnace 23 through line 25 and thence discharged into the top of a tower 27 which is preferably packed with kaolin or Florida earth, bauxite and the like, which latter has a catalytic effect, where they

35 are conditioned by the polymerization of unsaturated bodies contained in the vapors, such unsaturated bodies being olefins, diolefins, and similar unstable constituents. The temperature of the clay tower should preferably be such as to maintain the oil in a vaporous state, preferably

between 350° F. and 750° F. The pressure may be at atmospheric or above. The polymerization products are, for the most part, in a liquid form and are withdrawn from the bottom of tower 27 through pipe 28. Preferably a heavy gas oil is discharged from line 28 into tower 27 for the purpose of washing the clay to assist in the removal of the heavy fractions and/or polymerization or condensation products from the clay or other material in chamber 27. The hydrocarbon vapors thus treated are withdrawn through lines 30 and 33 and are discharged into line 1 leading into coil 2 for further treating under cracking conditions. Preferably the vapors withdrawn from 27 through line 30 are discharged into valved line 32, thence into a fractionating column 31 from which the polymerization liquid portion not removed from the vapors through line 28 in tower 27 may be withdrawn from tower 31 through line 34, and the conditioned gas oil vapors substantially free of polymerization products are withdrawn overhead through line 35 and thence discharged into line 33 for transfer to the inlet side of coil 2.

While I prefer to treat the hydrocarbon oil in vapor form in reaction chamber 27, it is within the purview of my invention to operate in the liquid phase in chamber 27.

Referring back to the cycle stock treated in chamber 27, it is pointed out that the best operating conditions obtained in this chamber depend on the nature of the recycled oil, that is to say, depending on the boiling range of the recycled oil and on the amount of polymerizable material contained therein, as well as other factors. Generally, it may be said that good results are obtained by operating at a temperature within the range of from 350° F.-750° F., employing either atmospheric or a superatmospheric pressure of say from 1-3 atmospheres gauge, or higher, and permitting a sufficient time of contact between the recycled oil and the adsorbent, say from 10 seconds to 3-5 minutes, to permit the desired conversion.

It is pointed out with respect to the tempera-

ture of the vapors entering treating tower 27 that the same should be at least above the dew point, and preferably should be from 50°-100° F. above the said dew point.

It is further pointed out that not only polymerization takes place in chamber 27, but also that unstable aromatic compounds which contain two or more aromatic rings in a single condensed nucleus are decomposed and recombined in some manner which is not exactly clear, to form heavy hydrocarbons which are relatively poor in hydrogen content which may be retained in the adsorbent material or subsequently withdrawn through lines 28 or 34.

Many modifications of my invention may be made by those skilled in this art without departing from the spirit thereof.

What I claim is:

A process for the conversion of hydrocarbon oils which comprises passing the fresh oil to be converted through a cracking zone, contacting said oil within said cracking zone with an active cracking catalyst, maintaining said oil during passage through said cracking zone at a cracking temperature, keeping said oil in contact with said catalyst within said cracking zone for a period sufficient to convert a substantial portion thereof into motor fuel, thereafter fractionating the cracked products to segregate a condensate fraction consisting of insufficiently cracked constituents and a motor fuel fraction, passing said condensate fraction free of fresh oil constituents through a polymerizing zone, contacting said condensate within said polymerizing zone with an active polymerizing catalyst, maintaining said polymerizing zone at a temperature between about 350° F. and 750° F., keeping said oil within said polymerizing zone for a period sufficient to polymerize unsaturated constituents therein, separating high-boiling polymers from the remainder of said oil and thereafter combining the last-named oil with fresh oil passing through said first-named cracking zone.
